UNITED STATES PATENT OFFICE.

RICHARD BUSTEED, OF BROOKLYN, NEW YORK.

DESIGN FOR MONUMENTS OF EGYPTIAN OBELISKS.

SPECIFICATION forming part of Design No. 11,755, dated April 27, 1880.

Application filed March 22, 1880. Term of patent 7 years.

To all whom it may concern:

Be it known that I, RICHARD BUSTEED, of Brooklyn, in the county of Kings and State of New York, have originated and invented 5 a new and useful Design for Monuments of Egyptian Obelisks; and I do hereby declare that the following is a full, clear, and exact description thereof, reference being had to the accompanying drawings, forming a part of 10 this specification.

Figure 1 is a perspective view of my monument, and Fig. 2 a plan view of the same.

The obelisk is mounted upon a pedestal, *a*, consisting of four steps. The corners of the 15 upper three of these steps are ornamented and concealed by cornices *A*. Upon these cornices are mounted pedestals *b*, with candlesticks, four in number. In practice it will be preferable to have electric lights at the tops 20 of these candle-sticks, and also an electric light at the top of the obelisk. At the four corners of the pedestal are the pedestals *B C* *D E*. The first three may have any figures or 25 designs, and the last one, *E*, a globe, *F*, with an American eagle, *G*, perched upon the globe. Four fountains, *g*, will also be arranged around

the pedestal *a*. Encircling the whole will be a fence or palisade, *H*, and at equidistant points along such palisade will be four pedestals. On these it is proposed to place the 30 recognized emblems of Europe, Asia, Africa, and America.

What I claim as my design is—

The design for ornamenting an obelisk, consisting of seven steps as a pedestal, *a*, for the 35 same, four cornices, *A*, concealing the corners of the upper three steps of pedestal, the four pedestals on said cornices, the candlesticks upon these pedestals, the corner-pedestals *B C* *D E*, the globe and eagle on pedestal *C*, the four 40 surrounding fountains *g*, the palisade *H*, and the four pedestals *I*, at points equidistant from each other along the palisade, substantially as shown.

In testimony that I claim the foregoing 45 my own I affix my signature in presence of three witnesses.

RICHARD BUSTEED.
